(57) CLAIM

The ornamental design for a shoe as shown and described.

DESCRIPTION

1. Shoe

1.1 : Front

1.2 : Back

1.3 : Left

1.4 : Right

1.5 : Top

1.6 : Bottom

1.7 : Perspective

The reproductions of the design show a left shoe, the corresponding right shoe is omitted as it is the mirror image of the shoe shown in the reproductions. The characteristic features of the design reside in the shape and pattern of the shoe sole and upper as shown. The shoe upper consists of leather and woven sections. The woven part is a radiating design located on the instep. The rubber shoe sole has a snake-like pattern, while the foam section of the shoe sole has a surface with granular bumps. The product has both shoelaces and a Velcro strap.
